Leo Lombardi, 907 W. 17th St., Los Angeles, Calif.

Filed Feb. 26, 1962, Ser. No. 68,989

Term of patent 14 years

(Cl. D34—5)

FIG. 1.

FIG. 2.

FIG. 3.

FIG. 4.

FIG. 1 is a plan view of the table showing my new design,

FIG. 2 is a side elevation thereof,

FIG. 3 is an elevation as seen from one end, and

FIG. 4 is an elevation as seen from the opposite end.

The fragmentary broken line showing of a game board is for illustrative purposes only.

The table is lined to indicate transparency.

I claim:

The ornamental design for a movable table for a game board, substantially as shown and described.
